UNITED STATES PATENT OFFICE.

FRANK J. BUFF, OF MILWAUKEE, WISCONSIN.

THILL-CO尤LING.

SPECIFICATION forming part of Letters Patent No. 509,017, dated November 21, 1893.

Application filed July 22, 1893. Serial No. 481,202. (No model.)

To all whom it may concern:

Be it known that I, FRANK J. BUFF, of Milwaukee, in the county of Milwaukee and State of Wisconsin, have invented a new and useful Improvement in Thill-Couplings, of which the following is a description, reference being had to the accompanying drawings, which are a part of this specification.

My invention has relation to improvements in thill-couplings, more especially of a form known as anti-rattlers.

In the class of thill couplings in which forward-extending arms are provided having inward-extending lugs at their front ends to receive the eye of the thill, it is important that one of said forward-extending arms should be made laterally adjustable, so as to provide for the ready insertion of the thill eye, and the accurate and even reception therein of the lugs. It is, therefore, the object of my invention to embody this feature in a simple and improved structure; and with this end in view the invention consists of the devices and parts as hereinafter described and claimed, or their equivalents.

In the drawings, Figure 1, is a vertical sectional view on the line 1—1 of Fig. 2. Fig. 2, is a horizontal section on the line 2—2 of Fig.

1. Fig. 3, is a vertical section on the line 3—3 of Fig. 1. Fig. 4, is a perspective view of the adjustable arm, and Fig. 5, is a detail perspective view of one of the bushings inserted between the end of the thill-eye and the arm.

Like numerals of reference denote like parts throughout the several views.

Referring to the drawings, the numeral 1 indicates a clip adapted to be secured to the fore-axle of the vehicle. The forward leg of this clip is provided with a lateral extension 2, from which, in turn, extends forward an integral arm 3, provided at its forward end with an inward-extending conical or tapering bearing lug 4. A bolt-hole 5 passes through this arm and through the lug. The rear side of the forward leg of the clip is provided with a recess 6, having an inward tapering bottom, and inward tapering sides, as clearly shown in Figs. 2 and 3.

The numeral 7 indicates a removable and adjustable arm, said arm having at its rear end an inward-extending integral lug 8, adapted to be fitted into the recess 6, and having

its inner side face, and its edges, tapering or beveled to correspond to the tapers or bevels of the bottom and bordering edges of the recess. The inward-extending lug is somewhat less in width than the arm of which it forms a part, whereby two shoulders 9, 9 are formed, adapted, when the lug is in place, to bear against the metal of the fore-leg of the clip as shown in Fig. 3. The provision of the inward-tapering bottom and sides of the recess, and the corresponding tapers of the lug 8, permit of the ready insertion and removal of the lug, inasmuch as when being inserted or removed the narrowest portion of the lug, both horizontally and vertically, is registering with the widest portion of the recess. The forward end of arm 7 is provided with an inward-extending conical or tapering bearing lug 10, similar in all respects to the lug 4, said lug 10, and the arm 7 at this point being provided with a bolt-hole 11.

The numeral 12 indicates a thill, the thill-eye 13 of which is in the form of a double tapering socket, that is, the tapers being from opposite sides inward to a medial or central point. These inward tapering portions of the thill-eye are lined with bushings 14, 14, of any suitable material, such as leather, rubber, or anti-friction metal.

In properly adjusting the device, one side of the thill-eye is passed over the tapering lug 4, and the rear inward-extending lug 8 of arm 7 inserted in its recess 6, the conical or tapering lug 10 of said arm being passed into the opposite side of the thill-eye. After this a bolt 15 is passed through the registering apertures of the arm, and held in place securely by means of the end nuts 16, 16. The relative position of the parts as just described is shown clearly in Fig. 2.

In the form of construction herein shown and described, it will be seen that all strain directly on the connecting bolt is provided against, as the draft or pull of the thill is exerted against the conical lugs whereby wear on the bolt, and consequent rattling of the parts, is prevented.

The bushings 14, 14 inserted in the thill-eye, of course lessen friction between said thill-eye and the conical lugs, and to a great extent prevent wear between these parts. Any slight wear that may occur, however, can be

provided for by the adjustment of the arm 7; or in case of excessive wear, the end friction bushings can be removed, and new ones substituted therefor. The point at which the greatest strain is liable to occur, however, is between the inner sides of the arms 3 and 7 and the ends of the thill-eye. In order to take up this wear, all that is necessary is simply to insert washers 17 between the parts referred to, as shown clearly in Fig. 2, one of said washers being shown in the detail view Fig. 5. These washers can be readily placed in position by reason of the provision of the removable arm 7.

15 It will be seen that I provide a thill coupling in which not only simplicity, cheapness and general efficiency enter as important factors, but furthermore a construction wherein the liability of rattling is reduced to the minimum.

Having thus described my invention, what I claim, and desire to secure by Letters Patent of the United States, is—

1. In a thill coupling, the combination, of 25 an axle clip having the rear side of its fore leg adjacent to the axle provided with a recess, and having an integral arm projecting forward from the front face of the fore leg, said arm having an inward-projecting conical lug, an arm provided at its rear end with a lug adapted to fit in the recess of the fore leg of the clip, and to abut against the axle, and

provided at its forward end with an inward-extending conical lug, a thill, the eye thereof being of double conical form to receive the 35 lugs, and a bolt passing through the arms and through said lugs, substantially as set forth.

2. In a thill coupling, the combination, of an axle clip having the rear side of its fore 40 leg adjacent to the axle provided with a recess, said recess provided with an inward-tapering bottom and inward-tapering sides, the clip also having an integral arm projecting forward from the front face of its fore leg, 45 said arm having an inward-projecting lug, an arm provided at its rear with an inward-extending lug, fitting the recess of the fore leg of the clip and abutting against the axle, the edges and inner face of said lug tapered 50 or beveled to register with the corresponding bevels of the recess, and said arm also provided at its forward end with an inward-extending lug, a thill, the eye thereof adapted to receive the inward-extending lugs at the 55 forward ends of the arms, and a bolt passing through the arms and forward lugs thereof, substantially as set forth.

In testimony whereof I affix my signature in presence of two witnesses.

FRANK J. BUFF.
